DESIGN FOR A DISPLAY RACK

Albert E. Ritchie, Buffalo, N. Y., assignor to The Wildroot Company, Inc., Buffalo, N. Y., a corporation of New York

Application May 26, 1934, Serial No. 51,932

Term of patent 3½ years

To all whom it may concern:

Be it known that I, Albert E. Ritchie, a citizen of the United States, residing at Buffalo, in the county of Erie and State of New York, have invented a new, original, and ornamental Design for a Display Rack, of which the following is a specification, reference being had to the accompanying drawing forming part thereof.

The figure in the accompanying drawing is a perspective view of a display rack, showing my new design.

I claim:

The ornamental design for a display rack, as shown.

ALBERT E. RITCHIE.
